CLAIM

The ornamental design for a play yard, as shown and described.

DESCRIPTION

FIG. 1 is a top, front, right side perspective view of a play yard showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof, and,

FIG. 8 is a top, front, right side perspective view of the play yard showing in an environment in which it may be used. The deemphasized lightened portions surrounded by broken lines and the broken lines representing the boundary are for environmental and illustrative purposes only and form no part of the claim.

1 Claim, 8 Drawing Sheets(56)
